D. L. DAVIS

PROCESS OF PRODUCING POLO FELT

Filed Jan. 14, 1921

Inventor
David L. Davis.

By his Attorney
Alfred H. Koch

UNITED STATES PATENT OFFICE.

DAVID L. DAVIS, OF SOUTH NORWALK, CONNECTICUT, ASSIGNOR TO DAVIS-POPE COMPANY INCORPORATED, OF SOUTH NORWALK, CONNECTICUT, A CORPORATION OF CONNECTICUT.

PROCESS OF PRODUCING POLO FELT.

Application filed January 14, 1921. Serial No. 437,162.

To all whom it may concern:

Be it known that I, DAVID L. DAVIS, a citizen of the United States of America, residing at South Norwalk, Fairfield County, State of Connecticut, have invented certain new and useful Improvements in Processes of Producing Polo Felt, of which the following is a full, clear, and exact description.

This invention relates to an improvement in the process of producing polo felt intended for use in the manufacture of hats or other articles of apparel. My improved process is more particularly a finishing process by means of which the surface of fur or hat-felt is changed so as to have the same appearance as polo cloth.

So far as I am aware, I am the first to produce a hat felt having a polo-cloth effect, this term being applied for the reason that the felt has substantially the same appearance as polo cloth.

My improved process produces a felt which is very desirable on account of its handsome appearance, especially when made up in the form of a hat, and I have found that my improved process produces a felt which renders articles made therefrom, more especially hats, very salable on account of the enhanced appearance thereof.

Referring to the drawing, Fig. 1 illustrates a side view of a rotary abrasive device to carry out the first step of the process;

Fig. 2 illustrates a similar view of a device to carry out the second step in the process;

Fig. 3 illustrates a side view of a device to carry out the third or buffing step of the process;

Fig. 4 illustrates a device to carry out the fourth or blocking step of the process;

Fig. 5 illustrates a device to carry out the fifth or nap raising step;

Fig. 6 illustrates a device to carry out the sixth or air blasting step;

Fig. 7 illustrates a device to carry out the clipping step; and

Fig. 8 illustrates a device to carry out the twisting operation.

In the production of my improved polo felt, I utilize ordinary fur felt which I treat in a special manner now to be described. To produce my polo felt, I first subject fur felt to the action of an abrasive element lightly applied to the fur side of the felt, to take off the fuzz or loose threads, so to speak. After

having removed the fuzz, I next subject the fur side of the felt, which has been abraded, to the action of a fine wire brush, which acts to raise the nap slightly to provide a velvety appearance. After the felt has been acted upon by the fine wire brush, I then buff the felt, to polish the same, the polishing being accomplished by a felt buffing wheel, white felt being preferably used for the buffing step. I then place the felt, treated as above, over a block and iron it to conform it to the shape of the hat. After the felt is blocked and ironed, I subject same to the action of a rotary bristle brush to raise the nap. I then direct a blast of air against the raised nap to cause same to stand up, or stick out from the body of the felt, and also to blow out the dust, etc. I then next clip off the upstanding nap to about one-eighth of an inch with what is known as a velour clipper. After the nap has been clipped, I subject same to the action of a felt pad, which is applied in the form of rotary motions in various directions.

The thus finished product will have an appearance, as hereinabove described, substantially similar to polo cloth.

The several steps of my improved process can be carried out by various forms of mechanical devices. The devices herein illustrated disclose a means to produce the desired result. Referring to the drawing, Fig. 1 illustrates a rotatable disk 9 carrying an abrasive element, sand-paper, for instance, indicated by 10. To carry out the first step of the process, the felt, indicated by 11, will be applied to a support or board 12, and held against the abrasive element to have the fuzz or loose threads removed, the fur of the felt being indicated by 13. To carry out the next step, the felt will be subjected to the action of a wire brush 14, Fig. 2, to slightly raise the nap to produce a velvety appearance, the pressure of the brush being regulated by the regulating wheel 15 and cooperating threaded post 16. During this operation, the support 12 for the felt will be shifted over the surface of the table 17 in order that the entire surface of the felt can be treated. To carry out the next step in the process, the felt will be subjected to the action of a buffing wheel 18, (Fig. 3), made of felt (preferably white felt), the pressure of which will be regulated by a hand wheel 19

and threaded spindle 20. During the buffing step, the support 12 will be shifted over the surface of the table 21 in order that the entire surface of the felt can be treated. To 5 carry out the next step, the felt will be fitted over a block 22 (Fig. 4) and ironed, the iron not being shown as such a device is well known. After the felt is ironed, I subject same to the action of a rotary bristle-brush 10 23 (Fig. 5) to raise the nap. After the nap is thus raised, I subject the felt to the action of an air blast, indicated by 24 (Fig. 6). After the nap has been raised by the air-blast 24, I clip the same by means of a 15 clipper, indicated by 25 (Fig. 7), which is a fragmentary sectional view, enlarged, of the block and felt thereon. After the felt is clipped, I subject it to the action of a felt pad 26 (Fig. 8) which can be fastened to the 20 hand 27 of an operator. The felt pad will be applied to the felt in the form of rotary motions in various directions to twist the threads out of their natural state. For instance, the pad may be moved to the right in 25 the form of circular motions; then in a direction at a right angle to said movement to the right; then transversely of said two motions, and so on in various directions. During this latter step, in the operation the 30 felt will be preferably dampened. Fig. 2 is a fragmentary section view of a block and the felt thereon which is subjected to the action of the felt pad.

Having described my invention, what I 35 claim and desire to secure by Letters Patent is:—

1. The method of producing polo felt con-

sisting in subjecting the felt to the action of an abrasive agent, thereafter raising the nap and finally subjecting the raised nap to the 40 action of an element to twist the same.

2. The method of producing polo felt consisting in subjecting the nap of the felt to the action of an abrasive agent to remove the fuzz therefrom, then raising the nap, then 45 polishing the raised nap, and finally subjecting the polished raised nap to the action of an element operating in various directions, to produce a twisted effect in said nap.

3. The method of producing polo felt 50 consisting in subjecting the nap of the felt to the action of an abrasive agent to remove the fuzz therefrom, then polishing the nap, then raising the nap, then clipping the ends of the nap, and finally subjecting the clipped 55 nap to the action of an element operating in various directions, to produce a twisted effect in said nap.

4. The method of producing a hat consisting in first subjecting the nap of the felt 60 to the action of an abrasive agent to remove the fuzz therefrom, then raising the nap, then polishing the nap, then ironing the same, then raising the ironed nap, and finally subjecting the raised nap to the action of an 65 element operating in various directions, to produce a twisted effect in said nap.

Signed at South Norwalk, Conn., this 8th day of January, 1921.

DAVID L. DAVIS.
